UNITED STATES PATENT OFFICE.

WILLIAM TILSON, OF HERRIN, ILLINOIS.

AEROPLANE.

1,400,582.

Specification of Letters Patent. Patented Dec. 20, 1921.

Application filed April 16, 1921. Serial No. 462,011.

To all whom it may concern:

Be it known that I, WILLIAM TILSON, a citizen of the United States, residing at Herrin, in the county of Williamson and State of Illinois, have invented certain new and useful Improvements in Aeroplanes, of which the following is a specification, reference being had to the accompanying drawings.

10 This invention relates to improvements in aeroplanes, and more particularly to improvements in the arrangement of the supporting surfaces thereof.

An important object of the invention is 15 to provide in combination with a stationary main plane, an auxiliary plane arranged above the main plane in spaced relation thereto, which is pivotally mounted so that the angle of incidence thereof may be altered 20 in accordance with the desires of the aviator. This arrangement will permit increasing of the effective lift of the main plane, and the auxiliary plane may furthermore be employed as a means for checking the speed 25 of the plane during landing in order that landing upon more restricted surfaces may be facilitated.

Other objects and advantages of the invention will become apparent throughout 30 the following description.

In the accompanying drawings wherein for the purpose of illustration is shown a preferred embodiment of my invention, and wherein like reference characters designate 35 like parts throughout:

Figure 1 is a front elevation showing an auxiliary plane constructed in accordance with my invention applied to the main plane of an aeroplane;

40 Fig. 2 is a side elevation thereof, and Fig. 3 is a plan view thereof.

Referring now more particularly to the drawings, the numeral 10 indicates a main plane, in the case of a biplane the upper 45 plane thereof, having secured to the upper surface thereof a plurality of bearings 11 paralleling the edge of the main plane.

Rotatably mounted at the end of the bearings 11 is a shaft 12 to which are secured 50 normally vertically extending supports 13 forming the support for an auxiliary plane 14, the plane 14 being braced to the supports 13 in any desired manner, as indicated at 15. Secured to the forward and trailing 55 edges of the auxiliary plane 14 are the ends of a flexible cable 16 which pass about suit-

able guides 17 and secured to an adjusting lever 18, coacting with a segment 19 so that the plane 13 may be adjusted to alter the angle thereof and may be held in such adjusted position.

In the positioning of the auxiliary plane 14 above the main plane, the same may be given either forward or negative stagger as may be desired, but the forward edges of 65 the main and auxiliary plane will preferably substantially coincide. The connection of the adjusting mechanism at present represented by the cable 16 and lever 18 will preferably be such that when the lever is 70 at one limit of its movement the auxiliary plane substantially parallels the main plane. In other words, at the same angle of incidence thereas. Movement of the lever to the other extreme will cause the plane to assume an angle to the main plane, the forward edge thereof being elevated so that the auxiliary plane is moved beyond the efficient angle of incidence which is normally about 75 four degrees to the horizontal. In its normal position the auxiliary plane 14, which is sufficiently spaced above the main plane 10 so as not to interfere with the area of suction left thereof, will provide an additional 80 lifting surface and will increase the effective 85 area of the main plane. The auxiliary plane is useful either in checking the forward motion of the plane in landing or in increasing the lift in rising from the ground.

From the foregoing it is believed to be 90 obvious that by the arrangement hereinabove set forth the effective lifting area of the main plane will be increased and that the auxiliary plane may be employed either for increasing the effective lift of the plane 95 or for checking the forward motion thereof, the latter result being accomplished by elevating the forward edge of the auxiliary plane beyond the efficient angle of incidence thereof. It will furthermore be obvious 100 that certain changes in the shape, size and arrangement of the main and auxiliary wings may be resorted to without in any manner departing from the spirit of my invention, and I accordingly do not limit myself to the specific arrangement hereinabove set forth and illustrated in the accompanying drawings, except as hereinafter claimed.

What I claim is:

1. In an aeroplane, the combination with 110 a fixed main supporting plane thereof, of a pivotal support extending longitudinally of

- the main plane, vertical uprights carried by the pivotal support, an auxiliary supporting plane secured to said uprights and normally having the same angle of incidence as the 5 main plane, and means for shifting said auxiliary plane upon the mountings thereof to increase the angle of incidence.
2. In an aeroplane, the combination with a fixed main support plane, of bearings carried by the main plane upon the upper surface thereof, a shaft mounted in said bear-

ings, normally vertical uprights secured to said shaft, an auxiliary plane secured to said uprights and normally having the forward edge thereof substantially above the 15 forward edge of the main plane, and means for shifting said auxiliary plane to alter the angle of incidence thereof.

In testimony whereof I hereunto affix my signature.

WILLIAM TILSON.
